UNITED STATES PATENT OFFICE

HENRY C. CALDWELL, OF BUFFALO, NEW YORK, ASSIGNOR TO CALDWELL EXPERIMENTAL CORPORATION, OF BUFFALO, NEW YORK, A CORPORATION OF DELAWARE

HEAT GENERATOR

Application filed September 16, 1926. Serial No. 135,831.

My invention relates in general to heat generators, used in connection with gas, in which the mixture of the gas and the air, as well as the combustion thereof, occurs within the device. This is to be contrasted with ordinary gas burners in which the gas and the air are first mixed before being passed into a chamber or spreader, whence the mixture flows and after which it is ignited.

As a result of numerous experiments, I have discovered that gas is most efficiently burned by being projected into the atmosphere through a plurality of minute orifices. Such efficiency, however, can be best attained when the control of the size of each orifice is at or near the mouth thereof, whereby the velocity of the gas being supplied thereto is not reduced before it reaches the mouth of the orifice, as is the case in the ordinary gas burner where a regulating valve or shut-off cock is arranged some distance behind the orifice. However, the great drawback to the practical embodiment of such a device is that when the orifices are made fine enough to accomplish efficient results, they become easily clogged, or burned out, thus requiring constant cleaning or renewal.

It has been an object of my invention to provide a device having a plurality of minute gas openings, which may be easily and quickly cleaned, should they become clogged. Moreover, these openings will not easily burn out, and will not be readily damaged.

Another object has been to provide a device in which combustion shall occur within the device, and in which back-firing shall be obviated.

Furthermore, my device is of such a nature that the air supplied to the mixture shall be controlled so that there will be no surplus air which would chill the refractory element of the burner.

Moreover, it has been an object to provide a device in which the heat generated shall intensify the combustion of the elements and thereby produce an increased velocity within the heating element of the generator, so that the gases will be more efficiently burned. The velocity within the heating element is fur-

ther increased by providing a strong draft through the generator.

Another object has been to provide a device by which the pressure of the gas in the supply pipe may be indicated.

The above objects and advantages have been accomplished by the device shown in the accompanying drawings, of which:

Fig. 1 is a fragmentary part of my generator, partly in section, showing the mixing unit thereof in its closed position.

Fig. 2 is a similar view showing the mixing unit in a partly open position.

Fig. 3 is an enlarged, fragmentary, sectional view, showing the details of the mixing unit.

Fig. 4 is an enlarged, fragmentary, view of a portion of the periphery of the piston of the mixing unit.

Fig. 5 is a fragmentary, sectional view of a modified form of my device.

Fig. 6 is a fragmentary, exterior view of my device, showing certain modifications.

Fig. 7 is a reduced exterior view, showing one form of application of my invention.

Fig. 8 is a reduced view of my invention as applied to a steam boiler, also showing an automatic heat control.

My device comprises in general a mixing unit 10 and a refractory element 11. The refractory element shown in Figs. 1 to 4, inclusive, and Figs. 6, 7, and 8, comprises a cylinder 12 within which a piston 13 is slidably mounted. The piston is closely fitted within the cylinder 12, and it is mounted upon the gas supply pipe 14. The piston with the supply pipe 14, it will be clear, is stationarily carried by the gas main (not shown). The cylinder 12 is movable over the pipe 14 and the piston 13. The cylinder 12 and piston 13 are preferably made of different metals so as to overcome the effect of expansion and contraction. The cylinder 12 is provided with a central hub 15 which is closely fitted about the pipe 14, and is provided with a suitable packing gland 16, whereby leakage of gas is prevented through the joint between the pipe and cylinder. The pipe 14 is provided with a number of radial

openings 17, whereby gas from the interior

thereof will be allowed to pass into the cylinder and behind the piston when the same is moved toward its open position. The piston 13 is provided on its periphery with a plurality of V-shaped grooves 20, tapering from the face of the piston which is toward the outside of the cylinder, backwardly toward the inner edge of the piston. These grooves are flared and inclined inwardly toward the back face of the piston, whereby the openings provided by the grooves between the periphery of the piston and the cylinder will be increased in size as the exposure of the surface of the piston is increased by the backward movement of the cylinder, so that the gas supplied to the generator is increased or decreased by the movement of the cylinder.

The refractory element 11 of my device is preferably in the form of a tube 25, arranged in front of the mixing unit 10 and of sufficient length to insure combustion occurring within the element, at any gas pressure supplied by the mains. This tube is, of course, made of suitable refractory material, so that the combustion taking place within it will cause its walls to become highly heated, thereby greatly adding to the efficiency of the device.

Carried by the cylinder 12 of the mixing unit is an air supply ring 26 formed with a face 27 and with an outer flange portion 28. An inner flange portion 29 is also provided, which securely fits over the cylinder 12 and extends inwardly a considerable distance beyond the inner face of the cylinder, thus forming a shield, whereby the gas will be permitted to travel a slight distance in front of the cylinder before being mixed with the air. In the face 27 of the ring, and preferably adjacent the inner flange 29 is arranged a plurality of fixed air openings 30. These air openings are of such a size and number, that they supply substantially the correct amount of air for the mixing unit under light loads. The outer flange 28 of the air supply ring extends over the outer end of the refractory tube 25, and a plurality of auxiliary air openings 31 is provided in this outer flange. These openings are so positioned that when the mixing unit is in its closed position, or when it is operating under very light loads, the auxiliary openings 31 will be closed by their overlapped positions with the refractory tube.

When, however, the load of the generator is increased and more air is needed, the backward movement of the outer flange 28 will serve to more or less expose the auxiliary openings 31, depending upon the position of the cylinder 12, as shown in Fig. 2, and thus supply the necessary additional air to the mixture. An adjustable ring 32 is rotatably disposed upon the outside of the outer flange 28 of the air supply ring, and is

provided with openings registering with the auxiliary openings 31. It will be obvious that by a relative rotation of the adjustable ring 32 the size of the auxiliary openings 31 may be predetermined to meet existing conditions.

Carried by the refractory tube 25 is a shield 35, which is preferably secured to the inner periphery of the tube and extends forwardly a distance sufficient to bring it into contact with the face 27 of the air supply ring when the mixing unit is in its closed position, as shown in Fig. 1. This shield will serve to deflect the air coming in through the auxiliary openings 31 and to direct it so that it will flow into the refractory tube in substantially the same direction as the air coming through the fixed openings 30.

In the drawings, I show two different means of causing the axial movement of the cylinder 12. In Figs. 1, 2, and 6 to 8, inclusive, I show means for producing a sliding movement. These means comprise an operating arm 36 which is pivotally mounted at its lower end to a bearing block 37. This block is carried by the supply pipe 14 and is securely fixed in the proper position upon the pipe by means of a set screw 38. The operating arm is connected at a point near its lower end to the cylinder 12 by means of a link 39. It is preferable to construct the operating arm 36 so that it is bifurcated at its lower end, thus straddling the bearing block 37. In such a construction, a link 39 is arranged at each side of the device. It is obvious that when the upper end of the operating arm 36 is moved backwardly or forwardly, the cylinder with the air supply ring will be likewise moved.

The other method of operating the cylinder is shown in the form of invention of Fig. 5. In this form I provide the supply pipe 41 with screwthreads 42 near its inner end. The hub 43 of the cylinder 44 is provided with interior screwthreads, which engage with the screwthreads 42 of the pipe. A handle 45 is provided on the hub 43, whereby the cylinder 44 may be rotated. It will be obvious that by the rotation of the cylinder, it may be moved backwardly and forwardly over the periphery of the piston. A suitable packing gland 46 serves to pack the joint between the pipe and the cylinder hub.

A pilot light 40 is preferably provided. This pilot light is connected to the supply pipe 14, and extends some distance in front of the piston 13.

In the form of invention of Fig. 5, I show a nose 47, preferably of refractory material and cone-frustum in shape. This nose serves to deflect some of the heat away from the parts of the mixing unit and also serves to reduce the noise of the burning gas within the generator. The nose is preferably screwthreaded to the pilot light 40 and is carried thereby.

In the form of invention shown in Fig. 6, a helical spring 50 is mounted upon the gas supply pipe 14 and arranged between the bearing block 37 and the packing gland 16. The normal tendency of this spring is to keep the cylinder 12 in its closed position over the piston 13. When gas pressure, however, exists within the supply pipe 14, it will be exerted against the inner surface of the piston 13 and serve to force the cylinder backwardly. This pressure will be taken by the spring, and the movement of the cylinder will be dependent upon the pressure existing within the pipe 14. Such pressure may be indicated on the side of one of the links 39, by providing a graduated scale 51. A pointer 52 is carried by the bearing block 37, and the scale is movable under this pointer.

In Fig. 6, I also show a locking device. This device comprises a vertically movable rod 53, which is carried by the operating arm 36. The upper end of this rod is pivotally attached to a handle 54, which is preferably moved back against the tension of a spring 55. The lower end of the rod 53 is preferably offset and is engageable with any one of a number of notches 56, formed in the outer surface of the supply pipe 14.

In Fig. 7, I show one form of application of my generator. The refractory element 11 is formed at its outer end preferably with a spherical member 60, lined with refractory material, which is preferably brought to a point 61 (as shown in dotted lines), where it meets the oncoming gas mixture, thereby producing a whirling action. Arranged on top of the spherical member 60 is a stack 62, also preferably lined with refractory material for a considerable distance above the spherical member 60. The stack 62 is shown relatively short, but this is made of suitable length in order to meet existing requirements. I have discovered that the longer the stack, the greater the velocity of burning, and, therefore, the higher the efficiency of the generator.

In Fig. 8, I show my generator as applied to a steam boiler. The refractory element 11 is supported by a closure plate 64, arranged preferably in the firedoor of the boiler. This closure plate is thoroughly sealed about the joint with suitable cement so that air can not enter the furnace at this place. The ash pit of the boiler and the firebox up to a point opposite the firedoor, are filled with ashes or with any suitable refractory material, thereby completely closing off the supply of air through the ash door 65 or clinker door 66. All places, at which air might be supplied or might leak into the firebox of the boiler, are closed, so that only air coming through the mixing element of my generator is supplied thereto. A refractory baffle 67 may be arranged within the boiler and located some distance in front of the inner end of the refractory element.

My heat generator is admirably adapted to automatic temperature control, and in Fig. 8 I have shown in a diagrammatical manner my device connected up to such a control. The operating arm 36 is connected with a cord 68 which passes around pulleys 69, 70, and 71. The end of the cord which passes around pulleys 71 is provided with a weight 72. The other end of the cord which passes around pulleys 70 is attached to the arm 73 of an operating motor 74. This motor and the means for actuating the same are standard articles of manufacture, and, therefore, not described in detail. As shown in the drawings, the mixing unit of my generator is held open, by the weight 72. When the temperature of the room being heated reaches the predetermined point, the operating motor 74 is actuated, which will pull the cord 68 so as to shut off the gas supply by moving the operating arm 36 to its closed position. Obviously, when the temperature has been decreased to the predetermined point, the operating motor 74 will again be actuated, thus permitting the weight 72 to move the operating arm 36 to its open position. When a temperature control is used in my device, it is necessary to supply the pilot light 75 with a separate source of gas. This pilot light is preferably extended through the refractory tube 25 in front of the mixing element, and is supplied with gas by means of a pipe 76 connected with the supply pipe 77.

Obviously, some modifications of the details herein shown and described may be made without departing from the spirit of my invention, or the scope of the appended claims, and I do not, therefore, wish to be limited to the exact embodiments herein shown and described, the forms herein shown and described being merely preferred forms thereof.

Having thus described my invention, what I claim is:

1. A heat generator comprising a stationary arranged gas supply pipe, a piston carried by the pipe, and a cylinder movably mounted on the pipe and engaging the piston, such piston being provided with a number of elongated V-shaped grooves in its periphery.

2. A heat generator comprising a stationary arranged gas supply pipe, a piston carried by the pipe, a cylinder movably mounted on the pipe and engaging the piston, such piston being provided with a number of elongated V-shaped grooves in its periphery, a refractory tube arranged in front of the piston, and an air supply ring carried by the cylinder and engageable with the tube.

3. A heat generator comprising a stationary arranged gas supply pipe, a piston carried by the pipe, a cylinder movably mounted on the pipe and engaging the piston, such

- piston being provided with a number of elongated V-shaped grooves in its periphery, a refractory tube arranged in front of the piston, and an air supply ring carried by the cylinder and engageable with the tube, the air supply ring being formed with a plurality of air openings.
4. A heat generator comprising a stationary arranged gas supply pipe, a piston carried by the pipe, a cylinder movably mounted on the pipe and engaging the piston, such piston being provided with a number of elongated V-shaped grooves in its periphery, a refractory tube arranged in front of the piston, and an air supply ring carried by the cylinder and engageable with the tube, the air supply ring being formed with a plurality of fixed air openings, and also with a plurality of auxiliary, adjustable air openings.
5. A heat generator comprising a stationary arranged gas supply pipe, a piston carried by the pipe, a cylinder movably mounted on the pipe and engaging the piston, such piston being provided with a number of elongated V-shaped grooves in its periphery, and means mounted on the pipe and connected with the cylinder for moving the cylinder inwardly and outwardly over the piston.
6. A heat generator comprising a stationary arranged gas supply pipe, a piston carried by the pipe, a cylinder movably mounted on the pipe and engaging the piston, such piston being provided with a number of elongated V-shaped grooves in its periphery, a refractory tube arranged in front of the piston, and a refractory cone mounted in front of the piston and projecting into the tube.
7. A heat generator comprising a stationary arranged gas supply pipe, a piston carried by the pipe, a cylinder movably mounted on the pipe and engaging the piston, such piston being provided with a number of elongated V-shaped grooves in its periphery, a refractory tube arranged in front of the piston, an air supply ring carried by the cylinder and engageable with the tube, and formed with a plurality of fixed air openings, and also with a plurality of auxiliary, adjustable air openings, and a movable ring provided with openings registerable with the auxiliary air openings.
8. A heat generator comprising a stationary arranged gas supply pipe, a piston carried by the pipe, a cylinder movably mounted on the pipe and engaging the piston, such piston being provided with a number of elongated V-shaped grooves in its periphery, lever means mounted on the pipe for controlling the movement of the cylinder, and means for locking the lever in any desired position.
9. A heat generator comprising a stationary arranged gas supply pipe, a piston carried on the pipe and engaging the piston, such
- piston being provided with a number of elongated V-shaped grooves in its periphery, lever means for controlling the movement of the cylinder, means for limiting the movement of the cylinder, and means for locking the lever in any desired position.
10. A heat generator comprising a stationary member, and an interengaging movable member, the joint between the members being smooth and unbroken, a plurality of V-shaped grooves formed in one of the members and providing unrestricted gas orifices between the members, means for moving one of the members, and thereby controlling the size of the orifices while maintaining the maximum velocity caused by the initial gas main pressure, and a refractory combustion chamber arranged immediately in front of the orifices.
11. A heat generator comprising a stationary arranged gas supply pipe, a piston carried by the pipe, a cylinder movably mounted on the pipe and engaging the piston, such piston being provided with a number of elongated V-shaped grooves in its periphery, and a refractory tube arranged in front of the piston.
12. A heat generator comprising a stationary arranged gas pipe, a piston carried by the pipe, a cylinder mounted on the pipe and engaging the piston, such piston being provided with a number of elongated V-shaped grooves in its periphery, and a refractory tube arranged in front of the piston.
13. A heat generator comprising a refractory combustion chamber, means located in front of the chamber for breaking up the gas into a plurality of thread-like jets, an air ring for admitting substantially all of the air to the chamber at one place and in quantities sufficient to produce immediate combustion at the place where the fuel and air first mix and means for controlling the size of the jets at their points of formation, whereby the initial gas pressure in the gas main will be maintained up to the place of formation of the jets and maximum velocity of the gas passing through the jets will be attained.
14. A heat generator comprising a refractory combustion chamber, means for supplying gas comprising interengaging stationary and movable members having orifices formed therebetween and located at the entrance of the chamber for breaking up the gas into a plurality of thread-like jets, means for controlling the size of the orifices, and an air ring adjacent the jets for admitting substantially all of the air to the chamber at one place and in quantities sufficient to produce immediate combustion.
- In testimony whereof, I have hereunto signed my name.

HENRY C. CALDWELL.
